(57) **CLAIM**

The ornamental design for a motorcycle throttle grip and foot peg, as shown and described.

DESCRIPTION

FIG. 1 is a bottom plan view of a motorcycle throttle grip and foot peg showing my new design wherein portions are illustrated in phantom and form no part of the claimed design;

FIG. 2 is a side elevation view thereof wherein portions are illustrated in phantom and form no part of the claimed design;

FIG. 3 is an opposite side elevation view thereof wherein portions are illustrated in phantom and form no part of the claimed design; and,

FIG. 4 is a top plan view thereof wherein portions are illustrated in phantom and form no part of the claimed design.
